UNITED STATES PATENT OFFICE

TAYLOR L. MILLER, OF SILVERTON, TEXAS

CARRYING HANDLE

Application filed April 15, 1930. Serial No. 444,529.

This invention relates to carrier devices and more particularly to a carrying handle for containers of various kinds.

An object of this invention is to provide a carrying handle which may be positioned about the package or container and which is adapted to hold a removable cover or the like upon the package.

A further object of this invention is to provide a carrying device which may be used in combination with a foldable box or receptacle so as to provide a substantial carrying handle by which the foldable receptacle may be moved from point to point.

15 A still further object of this invention is to provide a metal strap which is adapted to be positioned about the opposite sides and on the bottom of the package, the strap being adapted to removably receive a resilient handle 20 which, when positioned on the strap, will provide a convenient means for transporting the package and at the same time provide a locking member for the cover or top of the package, the strap being adapted to extend 25 through slots in the top of the package or box.

The above and various other objects and advantages of this invention will in part be described in and in part be understood from 30 the following detailed description of the present preferred embodiment, the same being illustrated in the accompanying drawings wherein:

Figure 1 is a detail perspective view of a 35 device constructed according to the preferred embodiment of this invention; and

Figure 2 is a transverse sectional view partly in detail taken substantially through the center of the device.

40 Referring to the drawings wherein like numerals of reference designate corresponding parts throughout the several views, the numeral 10 designates generally a box or receptacle which is provided with a removable lid or top 11. The box or receptacle 10 is preferably adapted to be constructed so as to be shipped in a "knocked down" condition and in order to obtain this purpose, the box is preferably constructed of substantially 45 heavy paper or cardboard and the lid 11 is

constructed in like manner, the lid 11 having depending flanges 12 which are adapted to extend downwardly along the opposite sides of the receptacle.

The lid 11 is provided with a slot or opening 13 on each side thereof, and a metal apertured strap 14 which may be of any desired width is adapted to extend downwardly along the opposite sides of the receptacle 10 and on the bottom of the receptacle. The 55 strap 14 is preferably U-shaped.

A removable resilient bail or handle 15 is secured in one of the apertures 16 in the strap 14, the bail 15 being of resilient construction and preferably of heavy wire or the like 60 which is provided with inwardly extending 65 tongues 17, the tongues 17 being adapted to hold the top 11 upon the upper end of the receptacle 10.

The strap 14 is adapted to extend upwardly and outwardly of the top 11 through the slot or aperture 13, and the bail 15 may be removably positioned in a selected aperture 16 in the strap 14. The bail 15 has been disclosed as having a horizontal portion 18 which 70 is adapted to be grasped by the hand and if desired, a tubular handle grasping member or the like may be positioned on the handle portion 18.

A pair of diverging portions 19 extend outwardly and downwardly from the handle portion 18, the diverging portions 19 terminating in the inwardly extending tongues 17. It is, of course, understood that the bail 15 80 may be constructed in the form of an arc or the like and I therefore do not wish to be 85 limited to the particular configuration of the bail herein disclosed.

In the use of this device, the supporting strap 14 is adapted to be positioned about the receptacle or box 10, and the free ends of the strap are projected upwardly through the slotted portions 13 in the cover or lid 11. The bail 15 may then be positioned in the selected apertures 16 in the outer or free ends 90 of the strap 14, whereupon the handle portion 18 of the bail 15 may be grasped and the package conveniently carried.

It is obvious from the foregoing that the lid 11 is securely held upon the box or re-

ceptacle 10 by means of the inwardly extending tongues 17 of the bail 15 so that the lid of the receptacle cannot be removed until the handle or bail 15 has been removed from the strap 14.

5 It will, of course, be understood that various changes and modifications may be made in the details of construction and design of the specifically described embodiment of the 10 invention without departing from the spirit thereof, such changes and modifications being restricted only by the scope of the following claims:—

What is claimed is:—

15 1. A carrying device of the character described comprising in combination with a receptacle having a slotted lid, a U shaped flat strap adapted to substantially surround the receptacle, said strap having longitudinally spaced apertures therethrough, and a bail removably engaging selected apertures in said strap.

20 2. A carrying device of the character described comprising in combination with a box having a removable slotted lid, a U-shaped flat supporting strap adapted to engage about the opposite sides and the bottom of said box, the free ends of said strap being adapted to extend upwardly and outwardly through the 25 slotted portions of said lid, said strap having longitudinally spaced apertures therethrough, and a bail having inwardly extending tongue portions removably engaging in selected apertures in said supporting strap, 30 said tongue portions being adapted to releasably lock said lid upon the box.

35 In testimony whereof I hereunto affix my signature.

TAYLOR L. MILLER.
